UNITED STATES PATENT OFFICE

WALTER R. MORTON AND FRANK C. WILLIAMS, OF AKRON, OHIO

HAIR DRIER

Application filed May 19, 1931. Serial No. 538,513.

This invention relates to hair drying devices, and more particularly to a drier which is adapted to use heated air.

An object of this invention is to provide a hair drying system of relatively simple construction which may be readily installed in a hair shampooing establishment, which is so constructed that none of the fumes emanating from the drier will be discharged into the room.

Another object of this invention is to provide in a drier of this kind means whereby a drying hood may be adjustably supported so that a person may sit in a chair or the like in front of the device in such a position that only the head of the person is enveloped by the drying hood.

A further object of this invention is to provide in a hood construction means whereby the heated air will be projected against the hair and head of the person so as to thoroughly dry all of the hair which is disposed within the drying hood.

A still further object of this invention is to provide in a device of this kind means by which the heated air may be used over again, the system including circulating means whereby the cooled air is drawn through the system from the drying hood and the heated air is projected into the drying hood from which point the heated air is drawn back into the system.

Still another object of this invention is to provide a system of this kind by means of which any desired number of drying hoods may be interposed in the system and any one or all of the hoods used at the same time.

The above and various other objects and advantages of this invention will in part be described in and in part be understood from the following detailed description of the present preferred embodiment, the same being illustrated in the accompanying drawings, wherein:

Figure 1 is a fragmentary detail perspective view of a device constructed according to the preferred embodiment of this invention, and

cal sectional view taken through one of the drying hood members.

Referring to the drawings wherein like numerals of reference designate corresponding parts throughout the several views, the numeral 10 designates generally a heater casing which has disposed therein heater coils 11 which may be heated in any conventional way, but in the present construction, the heater coils 11 are heated through the medium of a gas line 12 which is connected to a suitable source of gas supply and extends through an opening 13 in the housing or casing 10. The upper portion or top of the casing 10 is preferably tapered, as at 14, and a conduit 15 of elongated construction is connected to the upper portion 14 of the housing 10 by means of an elbow or connecting member 16. This conduit 15 may be extended to desired points about the room and is provided with a plurality of outlets 17 and pairs of outlets 18 disposed on opposite sides of the main outlets 17. A short length of pipe or conduit 19 is connected to the conduit 15 in the outlet 17 and in like manner, short lengths of pipe 20 are connected to the outlets 18.

A return conduit 21 is connected to the housing 14 by means of a tapering or diverging connecting member 22 within which a fan 23 is mounted, this fan 23 being adapted to draw air through the return pipe line 21 and force the air through the coils 11 and upwardly through the housing 10 and into the hot air conduit 15. An upwardly curved deflector 24 is disposed within the housing 10 and is adapted to deflect upwardly the air forced into the housing 10 by means of the draft fan 23. A door 25 is hinged to one of the side walls of the motor housing 22, and a switch 26 is carried by one wall of the housing 22 so that the fan motor 23 may be turned on from a point exteriorly of the motor housing 22.

A drying hood H is provided with an inlet pipe connection 27 which is adapted to telescope the pipe connection 19, this inlet pipe 27 slidably engaging the pipe 19. A weight or balancing member 28, which has a flexible member 29 connected thereto and which is

Figure 2 is an enlarged fragmentary verti-

trained over a pulley 30, is connected at the opposite end to the hood H and is adapted to hold this hood H in vertically adjusted position with respect to the pipe connection 19. 5 The hood H is also provided with side inlet pipe connections 31 at each side thereof which slidably engage the pipe connections 20. The hood H has one face thereof partially open, as at 32, so that the head of an individual may 10 be partially projected into the interior of the hood H.

A front wall 33 which is disposed on the front of the hood H adjacent the bottom is provided with a curved upper edge portion 34 15 for engagement about the head and neck of the individual and in like manner, an upper front wall member 35 extends downwardly from the upper edge of the hood H and is provided with a curved lower edge portion 36. 20 An outlet pipe connection 37 is connected to the lower end or bottom of the hood H and extends rearwardly therefrom so that an individual may be seated or disposed in a convenient manner so as to permit the head to be 25 projected into the interior of the hood H. A vertically disposed pipe 38 is connected to the rearwardly or angularly disposed outlet pipe 37 and this vertical pipe 38 slidably engages or telescopes a pipe 39 which is connected at one end to the return conduit 21.

The inlet pipe 27 is provided with a damper 40 so that the hot air passing downwardly therethrough and into the hood H may be regulated and in like manner, the pipe connections 31 on each side of the hood H are provided with dampers 41 so that the quantity of air passing into the hood H at each side thereof may be properly regulated. A main volume damper 42 is disposed within the hot 30 air pipe or conduit 15 intermediate the outlets 17 and 18 and the housing 10, so that the desired volume of air passing through the hot air conduit 15 may be properly regulated.

A top shield or deflector 43 is disposed 45 within the hood H adjacent the upper forward edge thereof, this shield 43 being of arcuate or curved construction so as to project the air onto the hair of the individual adjacent the forehead. A rear deflector 44 50 is hingedly mounted at its upper edge by means of hinged members 45 to the rear wall of the hood H, this rear deflector 44 being of arcuate construction so as to project the heated air against the lower ends of the 55 hair at the back of the head.

A toothed rack 46 is hingedly secured at its inner end 47 to the deflector 44 and this rack 46 extends outwardly of the hood H at the rear thereof, the teeth of the rack being 60 adapted to engage the wall of the hood H for adjustably supporting the deflector 44 within the hood. An outlet or overflow pipe 48 is connected at one end to the housing 10, the opposite end of the outlet pipe 48 being open 65 to the atmosphere so as to permit the dis-

charge of fumes or excess air at a point remote from the housing 10.

A back draft trap 49 is interposed in the outlet pipe 48, this trap 49 being of conventional construction so that no fumes from the outside will be permitted to pass into the housing 10. A conventional damper 50 is disposed within the outlet pipe 48. The housing or casing 10 may also be provided with a hinged door 51 so as to permit cleaning or the like of the housing. 75

In the operation of this device, the heating unit or member 12 may be set in operation so as to heat water or the like disposed within the heating coil 11. If desired, this heating coil 11 may be connected to any other desired heating unit, in which case the pipe connection 12 may be dispensed with. When the coil 11 is heated, the fan motor 23 may be started so as to start the circulation of air 80 within the system. The fan motor 23 will force air upwardly through the housing 10 and into the hot air conduit 15. The hot air in the conduit 15 will pass downwardly through the outlet pipe connections 19 and 20 85 and into the hood H. After passing through the hair and about the head of the individual whose head is disposed within the hood H, the air which will then be cooled to some extent, will pass outwardly of the hood H 90 through the outlet pipe 37 and back into the casing 10 through the return conduit 21. Any number of hoods H may be connected to the hot air pipe 15 and any one or all of the 95 hoods used at the same time. 100

It is, of course, understood that various changes and modifications may be made in the details of construction and design of the above specifically described embodiment of this invention without departing from the 105 spirit thereof, such changes and modifications being restricted only by the scope of the following claims.

We claim:—

1. A hair drier of the character described 110 comprising an air heating member, a hot air conduit connected to said member, a cold air conduit connected to said member, means for forcing air from said cold air conduit through said member to said hot air conduit, a hair drying hood, slidable connecting means connecting said hood with said cold air conduit, slidable connecting means connecting the top of said hood with said hot air conduit, and slidable connecting means 115 connecting each side of said hood with said hot air conduit. 120

2. A hair drier of the character described comprising an air heating member, a hot air conduit connected to said member, a cold air conduit connected to said member, means for forcing air from said cold air conduit through said member and into said hot air conduit, a hair drying hood, telescoping pipe sections connecting the lower portion of said 130

- hood with said cold air conduit, telescoping pipe sections connecting the top of said hood with said hot air conduit, a damper in said latter pipe sections whereby to control the hot air entering the hood at the top thereof, telescoping pipe sections connecting said hot air conduit with each side of said hood, and dampers disposed within said latter pipe connections whereby to permit control of the hot air entering the sides of said hood.
3. A hair drier of the character described comprising a heating member, a hot air conduit connected to said member, a cold air conduit connected to said member, a hair drying member, slidable connecting means connecting said hair drying member with each of said conduits, deflecting means disposed within said hair drying member whereby to deflect the hot air against predetermined points on the head of an individual disposed within said hair drying member, and means for adjustably mounting said deflecting means within said hood.
4. A hair drier of the character described comprising a heating member, a hot air conduit connected to said member, a cold air conduit connected to said member, a hair drying hood, connecting means connecting said hood with each of said conduits, an upper deflector disposed within said hood, a rear deflector, means for hingedly mounting said rear deflector within said hood, and adjustable means engaging said rear deflector and extending outwardly of the hood.
5. A hair drier of the character described comprising a heating member, a hot air conduit connected to said member, a cold air conduit connected to said member, a drying hood, slidable connecting means connecting the top of the hood with the hot air conduit, slidable connecting means connecting the bottom of the hood with the cold air conduit, means for directing hot air through the sides of the hood, and adjustable means engaging the hood whereby to hold said hood in vertically adjusted position.
6. A hair drier of the character described comprising a casing, air heating means disposed within the casing, a hot air conduit connected to the upper portion of said casing, a cold air conduit connected to the lower portion of said casing, a fume discharging conduit connected to the casing, a hair drying hood, slidable connecting means connecting the top of the hood with the hot air conduit, slidable connecting means connecting the bottom of the hood with the cold air conduit, and connecting means connecting the sides of the hood with said hot air conduit.
- 60 In testimony whereof we hereunto affix our signatures.

WALTER R. MORTON.
FRANK C. WILLIAMS.
